CLAIM

We claim the ornamental design for an automotive vehicle instrument cluster, as shown and described.

DESCRIPTION

FIG. 1 is a front-perspective environmental view of an automotive vehicle instrument cluster, of the new design; FIG. 2 is a rear-perspective view thereof;

FIG. 3 is a front view thereof;

FIG. 4 is a top view thereof;

FIG. 5 is a side view thereof;

FIG. 6 is a side view thereof, opposite that of FIG. 5; and,

FIG. 7 is a back view thereof.

The broken and dashed lines are for environmental illustrative purposes only and form no part of the claimed design.

1 Claim, 6 Drawing Sheets
